 Paris, France

Application June 20, 1940, Serial No. 341,575
 In France July 18, 1939

5 Claims. (Cl. 139-13)

The present invention has for object a device for controlling the heddle frames in a circular weaving loom of the type in which the warp threads are fed at right angles or approximately at right angles to the axis of the loom and the heddle-carrying frames are lowered by means of cams acting on levers in antagonism to the action of returning springs. The rotation of said cams is suitably connected to that of the shuttles. This device is adapted to ensure the engagement and disengagement, in the predetermined order in synchronism with the passage of the shuttles, of the heddle-carrying frames in their position at the lower end of their stroke.

According to this invention one of the elements of the linkwork controlling each heddle-carrying frame cooperates with a resilient pawl and ratchet device which the operator of the loom can place in position awaiting engagement or in position awaiting disengagement, by a single control. When the pawl and ratchet devices are set in position awaiting engagement, at any instant, their resiliency allows the control mechanism to operate until the respective heddle-carrying frames are brought to the lower end of their stroke by the action of the cams; they are then retained and hold the corresponding warp threads lowered until the operator acts on the pawl and ratchet devices so that the latter are resiliently urged to release the linkworks controlling the heddle-carrying frames; the latter will then be restored upwardly by their respective springs only in proportion as the cams release their control levers.

Owing to the control and engagement devices thus combined, it is possible to hold lowered all the heddle-carrying frames so that all the warp threads are below the path followed by the shuttles and leave the latter completely uncovered and accessible. As the lowering and retaining of the heddle-carrying frames are obtained in synchronism with the rotation of the cams and, consequently of the shuttles, this uncovering of the shuttles takes place without any catching or risk of breaking the warp threads, without it being necessary to stop the loom and without the operator having to touch the threads to move them apart.

The placing in position of the pawl and ratchet devices can be effected not only at will by the operator, but also automatically by the operation of a thread-protector so as to immediately produce the uncovering of the shuttles for the easy and rapid repairing of the broken thread.

An embodiment of a control device according

to this invention is diagrammatically illustrated in the accompanying drawings, by way of example, in its application to a circular loom in which the warp threads are fed at right angles or approximately at right angles to the axis of the loom.

Fig. 1 is a vertical half-section passing through the axis of the loom.

Figs. 2 to 5 are partial vertical sections showing 10 in different positions, the levers and cams relating to a pair of frames.

In Fig. 1, *a* designates the fixed circular well through which descends the linen cloth formed by the warp threads *1*, *2*, which are fed approximately horizontally with respect to said well by passing through the eyes of the heddles *b*₁, *b*₂. The frames *c*₁, *c*₂ in which said heddles are mounted are arranged in pairs around the well *a*, according to the faces of a vertical prism. They 15 are vertically guided by means of rigid rods *d*₁, *d*₂ sliding through plates *e* *f* secured to the framework *g* which is diagrammatically illustrated in dot and dash lines, as well as by other rods parallel to the first ones, not shown in the drawings and adapted to prevent said frames from rotating about their axis.

All these frames are upwardly urged through the action of respective springs *h*₁ *h*₂ connecting the rods *d*₁ *d*₂ to the plate *f*.

30 For periodically lowering the frames, in this example, two cam shafts *i* are provided which are symmetrically placed on two opposite sides of the loom and each carrying as many cams *j*₁ and *j*₂ as there are frames *c*₁ *c*₂ on the corresponding 35 half of the circumference.

Each cam controls the corresponding frame through the medium of a batten *k*₁ or *k*₂ freely pivoting on a spindle *l* parallel to the shaft *i*, and of a link work comprising a bent lever *m*₁ or *m*₂ 40 and bonds *n*₁ or *n*₂, *o*₁ or *o*₂ connecting said levers to the battens and to the frames respectively. Of course, owing to the arrangement of the frames and consequently of the levers *m*₁ *m*₂ according to arcs of a circle, the bonds *n*₁ *n*₂ attached to the various levers have lengths proportional to the distances separating the latter from the corresponding spindles *l*.

Both cams *j*₁ and *j*₂ relating to one and the same pair of frames *c*₁ *c*₂ are rigidly secured so 50 that the latter are lowered in turn during each revolution of the shaft *i*, throughout the normal operation of the loom.

For that purpose, the rotation of the shafts *i* is connected to the rotation of the members 55 which ensure, on the one hand, the continuous

movement of the shuttles p in their circular guiding track q and, on the other hand, the downward progress of the fabric through the well a .

In order to maintain lowered, if need be, all the heddles, and consequently, all the warp threads, another spindle r is provided parallel to each spindle t , on said spindle r are secured resilient blades $s_1 s_2$ so arranged as to act as retaining pawls on the battens $k_1 k_2$ when they are pushed back by the respective cams.

The spindle r can be rotated through a certain angle either by hand, or under the action of a mechanism set in action by a thread-protector of any type (not shown) operating automatically under the action of the breakage of the weft thread of any one of the shuttles. In the normal position indicated in Fig. 2, the spindle r is rotated so that all the blades $s_1 s_2$ are lifted sufficiently for leaving the battens $k_1 k_2$ quite free to oscillate under the alternate control of the cams $j_1 j_2$ and of the returning springs $h_1 h_2$.

When the spindle r is rotated in the direction indicated by an arrow in Fig. 3, for instance, at the moment the battens k_1 are pushed back by the cams j_1 , the blades s_1 come under the upper noses of said battens, whereas the blades s_2 press upon the heads of the battens k_2 as illustrated.

The cams continuing their rotation (Fig. 4), cams j_1 abandon the battens k_1 which, under the action of the returning springs h_1 , then press against the blades s_1 , thereby retaining the frames c_1 and the respective threads in their lower position. At the same time, the battens k_2 pushed back by the cams j_2 allow the blades s_2 to come under their upper noses and are then engaged in the position in which the frames c_2 and the threads 2 remain lowered.

From this moment, all the warp threads form a single annular sheet above which the shuttles can continue to circulate. The loom can then be stopped and it is easy to effect the maintenance or repairs necessary.

When the normal operation of the loom is to be resumed, the spindle r is caused to pivot rearwardly, as indicated by the arrow of Fig. 5; the blades $s_1 s_2$ will consequently lift as soon as they are freed by the noses of the battens, that is to say during the first revolution of the cam shaft t ; so that the alternate lowering of the frames $c_1 c_2$ will begin again in concordance with the rotation of the shuttles and that the latter engage in the shed thus formed again.

It is to be understood that the embodiment illustrated is given herein only by way of example and that all constructional details can be varied without departing from the invention; in particular the flexible blades $s_1 s_2$ can be replaced by rigid fingers combined with springs or by any other members capable of acting as pawls, exerting a compression, traction or other action, for retaining the levers or battens $k_1 k_2$ lowered in antagonism to the action of the springs restoring the frames.

Likewise, in the accompanying drawings, and

in the foregoing explanations, a loom has been chosen by way of example, weaving in "plain" weave, but the invention can also apply to looms weaving in other weaves. In this case, the frames, battens, resilient blades and other corresponding members are arranged in series of three, four, etc., instead of being arranged in pairs.

I claim:

- 10 1. In a circular weaving loom the heddle-carrying frames of which are vertical and are moved vertically and downwardly by rotating cams, and upwardly by returning springs, a device for retaining said frames at the lower end of their stroke and for releasing them in concordance with the passage of the shuttles, comprising the combination of a series of levers loosely pivoted on a spindle, connected to the respective heddle-carrying frames, and normally pressed against the cams of a control shaft the rotation of which is connected to that of the shuttles about the axis of the loom, a series of retaining pawls adapted to act on said levers so as to hold the latter spaced from said cams, and control means for engaging said pawls on said levers and for resiliently urging them away from the latter.
- 15 2. A device for retaining the heddle-carrying frames of a circular weaving loom as claimed in claim 1, characterised by the fact that each pawl is constituted by a resilient blade one end of which is secured on a control shaft and the other end of which is adapted to yieldingly press on an end of the respective lever when the latter is in the position corresponding to the lifting of the respective heddle-carrying frame, and to then come, by resilient relaxation, in position to engage said lever when it is pushed back by the respective cam in order to retain said frame in its lower position.
- 20 3. A device for retaining the heddle-carrying frames of a circular weaving loom as claimed in claim 1, characterised by the fact that the means for controlling said device are adapted to be controlled at will by the operator in the direction for preparing the engagement of said levers and in the direction for preparing their disengagement, and to be controlled automatically by the breaking of any one of the warp or weft threads in the direction for preparing the engagement of said levers.
- 25 4. A device for retaining the heddle-carrying frames of a circular weaving loom as claimed in claim 1, in which the levers controlling said frames are provided at a suitable point with a nose placed in such a manner as to move in the areas of operation of said retaining pawl.
- 30 5. A device for retaining the heddle-carrying frames of a circular weaving loom as claimed in claim 1, in which the control cams are arranged in groups around the loom, in combination with means for controlling together said pawls corresponding to a plurality of heddle-carrying frames.

HENRI PELCÉ.
